DESIGN FOR A BRIDGE FOR AN OPHTHALMIC MOUNTING

James A. Sweeney, Providence, R. I., assignor to
Universal Optical Corporation, a corporation of
Rhode Island

Application September 13, 1935, Serial No. 58,544

Term of patent 14 years

To all whom it may concern:

Be it known that I, James A. Sweeney, a citizen of the United States of America, residing in Providence, county of Providence, State of Rhode Island, have invented a new, original, and ornamental Design for a Bridge for an Ophthalmic Mounting, of which the following is a specification, reference being had to the accompanying drawing, forming a part thereof.

Fig. 1 is a front elevation of a bridge for an ophthalmic mounting, showing my new design; Fig. 2 is a top plan view; Fig. 3 is an end view; and Fig. 4 is a sectional view of the same on line 4—4 of Fig. 1.

I claim:

The ornamental design for a bridge for an ophthalmic mounting, substantially as shown.

JAMES A. SWEENEY.
